UNITED STATES PATENT OFFICE.

REUBEN A. PUNNETT, OF ROCHESTER, NEW YORK, ASSIGNOR, BY MESNE ASSIGNMENTS,
TO LINEATIME MANUFACTURING COMPANY, INC., OF ROCHESTER, NEW YORK.

COPY-HOLDER.

1,266,622.

Specification of Letters Patent. Patented May 21, 1918.

Application filed February 10, 1913. Serial No. 747,262.

To all whom it may concern:

Be it known that I, REUBEN A. PUNNETT, of Rochester, in the county of Monroe and State of New York, have invented certain new and useful Improvements in Copy-Holders; and I do hereby declare the following to be a full, clear, and exact description of the same, reference being had to the accompanying drawings, forming a part of this specification, and to the reference numerals marked thereon.

My present invention relates to copyholders and more particularly to copyholders of the type in which a vertically disposed and vertically traveling copy-plate is actuated upwardly past a stationary line indicator and then caused to descend by virtue of its own weight, and it has for its object to provide a simple and efficient means for controlling the descent of the copy-plate and cushioning its fall to prevent jar and vibration. A machine of the general type mentioned is illustrated in the patent to Russell B. Griffith, No. 1,014,646, granted January 16, 1912, and for most purposes the present invention may be considered as an improvement thereon. Further objects of the invention are to render the retarding and cushioning means adjustable to compensate for wear and other changed conditions after a period of use and to prevent the rebound of the copy-plate following its descent. To these and other ends the invention consists in certain improvements and combinations of parts all as will be hereinafter more fully described, the novel features being pointed out in the claims at the end of the specification.

In the drawings:

Figure 1 is a rear elevation of a copy-holder constructed in accordance with and illustrating one embodiment of my invention;

Fig. 2 is a detail fragmentary and enlarged sectional view taken substantially on the line 2—2 of Fig. 1;

Fig. 3 is a horizontal section taken substantially on the line 3—3 of Fig. 2, and

Fig. 4 is a detail perspective view of the spring friction plate.

Similar reference numerals throughout the several figures indicate the same parts.

The precise machine illustrated is one designed particularly for use in connection with a typewriter and to this end comprises

an upright back frame 1 and a side frame 2 that extends forwardly and may be disposed along the side of the typewriting machine in such manner that a forwardly and rearwardly extending operating lever 3 substantially coincident therewith and having a finger portion 4 at the front will be accessible adjacent to the keyboard of the typewriter. The copy-plate 5 that is preferably of substantially the shape shown has suitable clips 6 at the top thereof for holding the pages of the copy and is guided to reciprocate vertically on the frame 1 by a centrally disposed guide rod 7 held offset from the rear face of the plate in brackets 8 and passing through a boss 9 that provides an extended bearing in the top rail 10 of the frame.

Supplementary guide rods 11 and 12 are also preferably provided but so arranged as to bear reversed relationship to the relatively movable parts from that of the guide 7. In other words, they are carried fixed on the frame 1 and pass through bracket bearings 13 and 14 secured to the bottom of the copy-plate, which brackets travel thereon.

The mechanism for elevating the copy-plate on its guide during which operation the writing on the page carried thereby is brought, a line at a time, above a suitable line indicator 15 suitably mounted on the frame 1 and having a portion spanning the front face of the plate, comprises, in the present instance, the operating lever 3, before described that is pivoted at 16 on a standard 17 rising from the side bar 2. The rear end of this lever is connected at 18 to a back lever 19 disposed transversely of the frame 1 and pivoted thereto at 20 at its opposite end. At an intermediate point, this back lever 19 has pivoted to it, as at 21, a vertically disposed clutch rod 22, the upper end of which is guided at 23 in the top rail 10 of the main frame. Its projecting end above the rail carries a lifting clutch 24 comprising a plate through which the rod 100 extends and that may oscillate thereon between pins 25 and 26. The guiding and lifting rod 7 on the copy-plate is passed through a suitable aperture in this clutch so that as the clutch rod 22 is elevated, the clutch will bind on the rod and raise the latter, but when the clutch rod is lowered will not be permitted to assume a sufficient acute angular relationship to cause a binding action.

Thus, when the copy-plate has been ele- 110

vated the distance of a line and it is required that the lifting clutch 24 be lowered with reference thereto to grasp the lifting rod 7 at a lower point, the copy-plate is supported against return movement by a similar clutch 27 that engages the lifting rod in the same manner under the influence of a spring 28 encircling the latter. The clutch 27 is fulcrumed on an extension of the frame at 29 so that as the clutch rod 22 normally passes freely through the same while being raised by the clutch 24, it at all times prevents the downward movement of the lifting rod 7 though allowing the latter to slide upwardly therethrough. When the last line of the page has been copied, the copy-plate is caused to descend to the lowered position, being approximately that shown in Fig. 1, by reversing the operating lever 3, that is, by raising it so that the back lever 19 is pressed down and the clutch rod 22 drawn with it. Upon such actuation of the parts, the lifting clutch 24 is released by an engagement with the rail 10 of the main frame that causes it to be straightened out horizontally so that it cannot bind upon the lifting rod. The retaining clutch 27 is released and caused to assume a similar position by the engagement of an abutment 30 therewith which compresses the spring 28. As the lifting rod is then unsupported by either clutch, it descends on its guide by gravity of the lowered position.

In the practice of my present invention, I provide a friction device for retarding the descent of the copy-plate that embodies a spring plate 31 which, in the present instance, is carried by the frame 1 and acts against the lifting rod and the guide 7. It is slightly bowed, as clearly shown in Fig. 2, and disposed against a flat face 32 on the boss 9 at one end against which flat surface it is held by a set screw 33. The lower end is turned inwardly and provided with a notch 34 that straddles the rod 7 and exerts resilient pressure thereon, the degree of which pressure may be varied by adjusting the set screw 33, for under the influence of the latter the curved plate may be flattened to a greater or less extent.

In addition to the friction brake 31, I provide at the base of each supplemental guide rod 11 and 12 encircling coil springs 35 and 36.

Of course, the downward travel of the copy-plate with any given load, can be so nicely adjusted by means of the brake 31 that a buffer at the bottom is hardly required, but inasmuch as the load, in the way of manuscript that is carried thereon, varies and it is necessary that the copy-plate also

descend when released without any load, the tension of the plate 31 is adjusted to give a slow but uniform descending movement 65 without load on the plate and the springs 35 and 36 working in conjunction therewith toward the end of the movement provide against shock due to the increased momentum of the copy-plate when its own 70 weight is added to.

It is important here to notice that the combined use of the buffer springs 35 and 36 on the one hand, and the friction brake 31 on the other, leads to an important result. 75 Were the springs used alone, it is evident that the copy-plate would rebound after engagement therewith upon reaching the limit of downward movement and not again assume its extreme lowered position because 80 its weight alone, unassisted by momentum, would be insufficient to again compress the springs, and the operating mechanism might be released to reengage the clutches just at this point. The friction device 31, 85 however, is sufficient to prevent any considerable rebound of this character and to hold the springs slightly compressed with a consequent relatively lower position of the copy-plate. 90

I claim as my invention:

1. In a copyholder, the combination with a support, a vertically disposed copy-plate and a guide fixed to one of said parts and slidably engaging the other, of means for elevating the copy-plate with a step by step movement, means for releasing said first mentioned means to permit the copyholder to descend, and a friction brake mounted on the other of said first mentioned parts and acting against the guide to check the descent of the copy-plate comprising a bowed spring plate disposed against a relatively flat surface and a securing and adjusting screw extending through the plate. 100

2. In a copyholder, the combination with a supporting frame having a horizontal top rail and a pair of vertically disposed guide rods, a vertically movable copyplate guided on the rods and a guide rod carried by the copyplate and guided in the top rail of the frame between the guide rods on the latter, of means for elevating the copyplate, means for releasing the latter to permit of its descent, and a friction brake mounted on the cross piece and acting against the central guide rod on the copyplate, said brake comprising a spring plate secured to the cross piece by a screw that also operates to regulate the tension of the brake. 110
